(57) **CLAIM**

The ornamental design for a display panel of a programmed computer system with a graphical user interface, as shown and described.

DESCRIPTION

FIG. 1 is a first view of a display panel of a programmed computer system with a graphical user interface;

FIG. 2 is a second view thereof;

FIG. 3 is a third view thereof;

FIG. 4 is a fourth view thereof;

FIG. 5 is a fifth view thereof;

FIG. 6 is a sixth view thereof; and,

FIG. 7 is a seventh view thereof.

The broken lines in the drawings are included for the purpose of illustrating environmental structure and form no part of the claimed design.

The subject matter shown in FIGS. 1-7 includes a process or period in which an image changes into another image. This process or period forms no part of the claimed design.

1 Claim, 7 Drawing Sheets
